UNITED STATES PATENT OFFICE.

CHARLES W. ROGERS, OF BALTIMORE, MARYLAND.

MACHINE FOR ROUNDING LEATHER.

SPECIFICATION forming part of Letters Patent No. 283,024, dated August 14, 1883.

Application filed March 10, 1883. (No model.)

To all whom it may concern:

Be it known that I, CHARLES W. ROGERS, a citizen of the United States, residing at Baltimore, Maryland, have invented certain new and useful Improvements in Machines for Forming Leather Round, of which the following is a specification, reference being had to the accompanying drawings, forming part hereof, in which—

10 Figure 1 is a front elevation of a machine embodying my improvements. Fig. 2 is a sectional view through the center thereof. Fig. 3 is a section through one end of the frame, the rolls being removed; and Fig. 4 is a plan view 15 of the forked lever for adjusting the rolls.

Like letters of reference indicate the same parts in all the figures.

The object of my invention is to furnish a set of rolls for the purpose of completing the filled 20 or partially-filled round leather without recourse to hand-labor.

In a former patent issued to me, numbered 251,293, and dated December 20, 1881, I show rolls for preparing the round leather, the finishing being done by hammering, which is a slow, tedious, and expensive process. By my 25 present improvement all hammering is dispensed with, the leather coming from the rolls in a finished state.

30 To this end my invention consists in the construction, arrangement, and combination of parts, which will be first fully described hereinafter, and then specifically pointed out in the claims.

35 Referring to the drawings by letter, A A' are standards, fastened in any suitable manner to a frame or table, and which afford bearings for the journals of the rolls. These standards are longitudinally slotted, as at a, Fig. 3, said slots 40 forming the bearings for the lower roll, B, and by virtue of their length vertically admit of an adjustment of said roll toward or from the roll C, which is journaled in said standards above the roll B, and is not adjustable. That portion 45 of the rolls B C which projects beyond the bearings is provided on one end with gear-wheels b' c', to cause the proper simultaneous rotation of the rolls, and on the other end with devices similar to those shown in my previous patent, 50 hereinbefore referred to. That portion of the rolls within or between the standards is formed to finish the round leather, the upper roll, C,

having four ribs, c², c³, c⁴, and c⁵, which register with and act in conjunction with four grooves, b² b³ b⁴ b⁵, formed in the lower roll, B.

55

The devices for adjusting the rolls are as follows: D is a standard located on the same frame or table as supports the standards A A', and centrally therewith, and has projecting upwardly therefrom a standard, d, having its upper end rounded to receive as a fulcrum a forked lever, E, having a main body, e, and three arms, e' e² e³, projecting from said main body on one side, and a central arm, e⁴, projecting therefrom in an opposite direction. 60 The standards A A' have each a lug, a², and the arms e' e² e³ of the lever E are notched at e⁵, to engage with the rounded top of the standard d and the lugs a², said lever being supported upon said standard and lugs. The arm e⁴ 70 is the handle for operating the forked lever, and thus raising the roll B into operative position, and the arm e⁵ is extended beyond the roll, and is provided with a suitable weight to cause it to fall when released, and thus allow the roll 75 to drop to its inoperative position. The arms e' e³ have a bearing against the lower side of the journals of the rolls.

In Figs. 5 and 6, I show the product of this machine, Fig. 5 showing it as it comes from c⁶ 80 b⁶, which are shown in my former patent, and Fig. 6 showing it as formerly completed by hand, but which I now complete with the machine. The roll c⁶ is provided with a knife, as shown, as is also the roll b⁶, which serve to cut 85 the channel in the folded strip to receive the stitches which bind said folded strip F and the filler-strip G together.

In operating this complete machine I take the ordinary flat strip, properly cut and shaved 90 to a uniform thickness, and, folding it in U shape, pass it through the rolls c⁶ b⁶, and when removed therefrom insert the filler-strip G, which is then secured by stitching through the channels cut by the knives on said rolls and 95 assumes the form shown in Fig. 5. This product is then passed through the rolls B C in channel b² b³ b⁴, as may be best suited to its size, and when it emerges therefrom it will be of the form shown in Fig. 5, after which it is brought 100 to the shape seen in Fig. 6 by being drawn through a die or draw-plate, or in any other desired manner.

The advantages accruing from the use of my

invention are obvious. Dispensing with the hammering formerly necessary, much manual labor is saved, curtailing the time, and consequently the expense, as well as avoiding the 5 irregularity of the hand-made product and the tendency to break the skin or body of the leather, which would involve the loss of the stock or the expense of skilled labor to repair. The product is always uniform in size, shape, 10 and density, and, being rolled, no danger of abrasure is incurred. The roll B may be removed from or replaced in the standards A A' by simply loosening the screw h and swinging the plate H downward on the screw h' as a 15 pivot, as shown in Fig. 3.

Having thus described my invention, what I claim, and desire to secure by Letters Patent, is—

1. The combination, substantially as described, of the rolls B and C, the former being mounted in movable bearings and the latter in fixed bearings, the roll B being provided with

grooves b^2 b^3 b^4 , shaper and channeler b^6 , and suitable means for adjusting it, and the roll C, with rings or collars c^2 c^3 c^5 and the shaper and 25 channeler c^6 , as and for the purpose set forth.

2. The combination, substantially as described, of the rolls B and C, the latter having fixed bearings, with the standards A A', having slots a , and the plate H, provided with 30 screws h and h' , as and for the purpose set forth.

3. The combination of the standards A A', having lugs a^2 , the standard D, having upright d , with rounded top, the forked lever E, having branches e^1 e^2 e^3 , provided with notches e^6 , 35 the part e^2 being weighted, as described, the roll B in a movable bearing, and the roll C in a fixed bearing, as set forth.

In testimony whereof I sign my name in presence of two witnesses.

CHARLES W. ROGERS.
